UNITED STATES PATENT OFFICE.

CHARLES W. BAILEY, OF LYNN, MASSACHUSETTS, ASSIGNOR TO JOHN HAMMOND STEWART, OF LYNNFIELD, MASSACHUSETTS.

COUNTER-SKIVING MACHINE.

Application filed February 11, 1922. Serial No. 535,702.

This invention relates to machines for skiving counter stiffener blanks and is of that type wherein the blanks are fed from a supply holder or stack to feed rolls, one of which is recessed to conform to the desired contour, and which properly present them to a fixed skiving knife.

Among the novel features of this machine is an improved mechanism for shaping the blanks to conform to the contour of the recessed roll and a novel form of feed roll used in conjunction therewith. In this mechanism the blank is held in position by a series of independent resiliently acting fingers engaging the blank along a plurality of closely spaced lines of contact and adjustable as a unit toward and from a skiving knife. The feeding mechanism engages the work between the lines of contact of the fingers.

This invention also provides an improved mounting for the knife and means by which it may be adjusted.

Further objects and advantageous details and combinations of parts will appear from a more complete description of the embodiment thereof disclosed in the accompanying drawings, in which

Figure 1 is an end view of the machine looking in the direction in which the work is fed.

Figure 2 is a side elevation of the machine.

Figure 3 is a longitudinal central section on line 3—3 of Figure 4.

Figure 4 is a plan view with portions broken away.

Figure 5 is a fragmentary sectional detail showing one of the presser fingers and adjacent parts.

Figure 6 is a section on line 6—6 of Figure 5.

Figure 7 is a fragmentary plan of the parts shown in Figure 5.

Figures 8 and 9 are a side elevation and plan respectively of the end portion of a presser finger, illustrating a modified construction.

Referring to the drawings, a table for supporting a stack of blanks to be fed to the knife is shown at 1, the blanks being positioned thereon between a series of retaining rods 2, having their upper ends reversely bent and seated within adjustable clamps 3, by which construction the rods 2 may be turned to adjust the spaces therebetween to

conform to different sizes of blanks. The rods 2 extend downwardly towards the platform or table 1 and are adjusted vertically in the clamps 3 so as to allow space for the passage thereunder of a single blank which may be fed to the skiving mechanism to be described.

The feed means for this blank comprises a slide 4, having a push plate 5 extending across the upper face of the table, this slide being moved toward and from a pair of feed rolls by mechanism to be described later. These feed rolls comprise an upper matrix roll 6 and a lower feed roll 7. As shown more particularly in Figures 3 and 5, the matrix roll 6 is recessed at 8 to conform to the shape of the blank to be skived. The blanks presented thereto by the feed plate 5 are pressed into the recess 8 by means of a series of presser fingers 9, arranged in parallel spaced relation in a series extending longitudinally of the feed rolls and fulcrumed on a shaft 10 extending parallel therewith.

Shaft 10 is fixed to a frame 100 slidably mounted on the machine frame and adjustable through bolt and slot connections 101 to move the fingers 9 substantially in the line of feed toward and from the skiving knife to be later described. It is found that different grades of work require different adjustments of the fingers relative to the knife for best results. The rear ends of these fingers or levers have attached thereto the upper ends of a series of coil springs 11, the lower ends of these springs being made fast to rods 12, passed down through the frame A of the machine and threaded in adjusting nuts 13. In order to allow room for these springs, they are placed in a series of rows in staggered relation, as shown more clearly in Figure 4. The lower ends of rods 12 extend within check nuts 14, positioned below the adjusting nuts 13. These check nuts extend sufficiently downward from the machine frame to be accessible at their lower ends to tools, by which they may be turned, transverse slots 15 being formed in the ends thereof for engagement by such tools.

Inwardly of the springs 11 each lever 9 passes through a notch in the upper end of a stop plug 16, these plugs having rotatably mounted in the lower ends thereof a series of screws 17, (see more particularly Figures 5 and 6,) threaded in a cross frame member 20. At their lower ends the screws 110

17 are provided with pins 18 passed transversely therethrough, which serve as handles by which they may be rotated for adjustment. At 19 are shown a series of nuts on 5 the upper ends of the screws, which bear beneath the cross member 20, and by which the upward position of the plugs 16 may be limited. The fingers or levers 9 may be provided at their forward ends with removable 10 wear plates 21, as shown in Figures 5, 8 and 9. In Figure 5 the wear member is shown as having a dovetailed portion at its rear end, fitting a dovetailed groove in the finger 9, while in Figures 8 and 9 the member 15 21 is shown as a rectangular plate made fast in its position by screws. By adjustment of the tension on the springs 11 and of the position of the plugs 16, the pressure exerted by the ends of the fingers on the work 20 presented to the gauge roll 6 and the limit of motion theretoward may be adjusted. The feed roll 7 is composed of a series of spaced serrated flange portions or discs 22 which extend upwardly between adjacent 25 fingers 9 to engage work as presented from the feed plate 5 and when the dovetail wear pieces shown in Figure 5 are employed, these members, which are removable by displacement laterally relative to their corresponding fingers, are held in position, when 30 the parts are assembled, by the flange or disk portions 32 on opposite sides thereof.

In order to insure that the blank is presented in proper timed relation to the 35 matrix roll 6, the following drive mechanism for the parts has been provided. Referring to Figure 1, at 25 and 26 are shown fast and loose pulleys carried by a main operating shaft 27, which carries on its inner end a gear 28 meshing with a gear 29 rotatable with a shaft 31 to which is fixed a gear roll 6. Shaft 31 also carries a gear 30 meshing with a gear 32 carried by a shaft 320. This gear 32 also meshes with a gear 33 journaled on a stud 330, and gear 33 meshes with a gear 34 fixed to a shaft 340 which carries the feed roll 7. This construction permits roll 7 to move vertically relative to the gauge roll 6 without interfering with the proper meshing of the actuating gears.

At the opposite end of the shaft 31 from the gear 30 is fixed a disc or wheel 49. Positioned adjacent to the disc 49 and journaled on the shaft 31 is a plate member 50 having an arcuate slot 51 therein, through which extends a stud 52 made fast in the disc 49. A nut 53 is threaded on this stud and by tightening of this nut the angular relation between the disc and plate may be adjustably fixed. The plate 50 carries an arm 54, to the end of which is pivoted at 55 one end of a link 56. The other end of this link is pivoted at 57 to a rocker plate 58 fulcrumed at 59 to the machine frame. A

link 60 is pivoted at one end at 61 to the rocker plate 58 and at its other end to the slide 4 at 62. It is therefore evident that by adjusting the angular position of the plate 50 on the disc 49, the timing of the motion of the slide 4 carrying the feed plate 5 may be adjusted relative to the recess 8 of the matrix roll so that the blanks may be positioned properly relative thereto.

The feed roll shaft 340 is mounted in 75 bearings in a yoke frame 35, and so that it may conform to different thicknesses of work, this yoke frame is spring supported from the main frame of the machine. For this purpose a coil spring, shown at 36, is 80 employed, which is seated within a boss 37, depending from the yoke 35 and surrounds a guide pin 38 projecting downwardly through a sleeve 39 threaded at 40 in the frame of the machine. The pin 38 is made fast at its upper end by a transverse pin 41 to the yoke 35, and the lower end of this pin passes through a perforation 42 in an inverted yoke member 43, made fast to the under side of the machine frame. Below this yoke frame a pair of collars 44 and 45, having handles 46 and 47 extending therefrom, are threaded on the pin 38 and provide means for adjusting the extent of upward motion of the feed roll. The spring 36 bears on the upper end of the sleeves 39, this sleeve having a series of perforations 48 at its lower end for the reception of a spanner wrench by which it may be turned 90 to adjust it vertically in the frame to adjust the tension of the spring 36.

The blanks as presented to the matrix roll are then to be skived by a fixed knife, shown at 70. This knife is made fast by a screw and slot connection, shown at 71, to the upper face of a knife holder or block 72, having a pair of rails 73 fixed at its upper surface and projecting toward the bite of the rolls 6 and 7, where they terminate in upwardly extending stop portions 74. The knife is adjusted on the block so that the ends of its cutting edge abut against the stops 74 and for this purpose a screw 75 is threaded in the support 70 beneath the knife, the head 76 of this screw projecting above its rear edge. The knife holder 72 is provided with laterally extending ears 77 which are mounted to slide in a guideway 78 in a vertical slide 780, the stud 79 surmounted by clamp nuts 80 and passing through slots 81 in these ears serving to hold the knife holder 72 in adjusted position. The rear end of this knife holder has a downwardly extending slotted yoke portion 82 for receiving the shank of a screw 83 threaded at 84 into the slide 780 and having a collar 85 fixed thereto engaging between the forks. The outer end of the screw 83 has a knurled adjusting head 86. The vertical slide 780 on which the knife

block is carried is provided with an indexing mark cooperating with a zero line on the knife block as shown at 87 on Figure 2. As the cutting edge of the knife is positioned against the stop plugs 74 this index is accurate at all times. The vertical slide 780 has a pair of outwardly extending ears 90 and 91, each having a vertical slot 92 therein for the reception of a stud 93 threaded in the frame of the machine, and on the outer end of each is threaded a clamping member 94. The ear 91 has a flange 95 at its lower end, through which passes an adjusting screw 96 threaded in the machine frame and carrying a knurled wheel 97, by which it may be turned, and a knurled adjusting nut 98 by means of which it may be fixed in position. By this knife mounting the vertical and horizontal positions of the knife may be accurately adjusted relative to the bite of the feed rolls.

It should be evident from the above that the blanks are fed from the stack in sequence beneath the lower end of the fingers 2 to the matrix roll 6 and feed roll 7, are pressed into the recess of the matrix roll, and in that position fed to the fixed knife which skives the blank to the proper form. The skived blank is then passed out of the machine over the upper surface of the knife.

Having thus described a machine embodying this invention, it should be evident that many changes and modifications might be made therein without departing from its spirit or scope as defined by the appended claims.

I claim:

1. A skiving machine comprising a recessed matrix, a skiving knife in cooperative relation to said matrix, a series of levers, means for pressing the ends of said levers against the work to retain it in the recess in said matrix, a stop block for each of said levers, and means for adjusting said blocks.

2. A skiving machine comprising a matrix roll, a skiving knife in cooperative relation to said roll, and a series of independently acting elements for pressing the work against said roll adjustable as a unit toward and from said knife and individually toward and from said matrix roll.

3. A skiving machine comprising supplemental rolls, one of which contains a matrix for giving contour to the piece to be skived, a knife placed to skive the articles delivered from between said rolls, resiliently acting pressers extending between the rolls toward the knife and yieldingly near the matrix

roll and being displaced from the latter against yielding resistance, a holder for said pressers movably mounted on the machine in a manner permitting it to be adjusted with the pressers toward or away from the knife and means for adjusting the several pressers together and individually toward and from said matrix roll.

4. A skiving machine comprising a matrix roll, a skiving knife in cooperative relation to said roll, and a series of independently acting elements for pressing the work against said roll adjustable as a unit toward and from said knife and individually and as a unit toward and from said matrix roll.

5. A skiving machine having a recessed matrix member, a knife for operating on work presented thereto by said member, a series of work feeding elements spaced laterally of the line of feed, a series of elements for pressing the work into the recess of said member each position in the space between adjacent feeding elements, and a work engaging wear piece detachably held in each pressing element by the feeding elements on opposite sides thereof.

6. A skiving machine having a recessed matrix member, a knife operating on work presented thereto by said member, work feeding members cooperating with said matrix member, elements for pressing the work into the recess of said member, and wear pieces associated with said elements and held in position by said feeding means.

7. A skiving machine having a skiving knife, a recessed matrix roll, a feed roll, a series of spaced work engaging flanges cooperating with said matrix roll to present work to said knife, a series of presser elements between adjacent flanges, and a wear piece associated with each element and detachable therefrom by a lateral motion relative thereto, said pieces when the parts are assembled extending between said flanges and being prevented from detachment from said elements thereby.

8. A skiving machine having a skiving knife, a recessed matrix roll, a feed roll, a series of spaced work engaging flanges cooperating with said matrix roll to present work to said knife, a series of presser elements between adjacent flanges and a wear piece having a dovetail connection with each element, said pieces when the parts are assembled extending between said flanges and being prevented from detachment from said elements thereby.

In testimony whereof I have affixed my signature.

CHARLES W. BAILEY.
